CORE REMOVING DEVICE

Raymond Frutchey, Easton, Pa., assignor to
Ingersoll-Rand Company, New York, N. Y., a
corporation of New Jersey

Application March 21, 1940, Serial No. 325,168

3 Claims. (Cl. 255—72)

This invention relates to core removing devices, and more particularly to a core removing device for both severing a rock core from the mass and removing it from a drill hole.

Heretofore, it has been customary to elevate the drilling or core forming mechanism to a considerable height above the core and then set off an explosive charge in the bottom of the kerf to rend the core free from the bed. This practice has the disadvantage, however, that when the core is freed it usually tilts against the side wall of the drill hole and makes it a difficult matter to insert the core into the core lifting device.

In accordance with the practice of the invention, it is contemplated to equip the core lifter with a holder for supporting an explosive charge. The assembly is then disposed in the kerf and the explosive charge is set off to break the core at its base. Thus, any tilting movement of the core that may be caused by the explosion will take place within the core lifter which may then be conveniently adjusted into gripping engagement with the core.

It is accordingly an object of the present invention to minimize the time required for placing the core lifter in the correct gripping relationship with the core and thereby shorten the idle periods between drilling operations.

Further objects will be in part obvious and in part pointed out hereinafter.

In the drawing accompanying this specification and in which similar reference numerals refer to similar parts.

Figure 1 is an elevation, partly in section, of the core removing device, and

Figure 2 is a transverse view, in elevation, taken through Figure 1 on the line 2—2.

Referring more particularly to the drawing, 20 designates, in general, the core removing device comprising a core lifter 21 arranged in a kerf 22 to encircle a rock core 23.

The core lifter 21, shown for the purpose of illustration, is of a known type comprising a casing 24 and a sleeve 25 movable longitudinally within the casing for effecting gripping engagement with and the release of the core 23. The lower part of the sleeve 25 is slotted longitudinally to provide flexible fingers 26 and on the inner surfaces of the lower parts of the fingers are serrations 27 for gripping the core 23.

The outer surfaces of the fingers 26, in the transverse plane of the serrations 27, have inclined surfaces 28 for cooperation with a coniform surface 29 in the front end of the casing 25

24 to flex the fingers inwardly and thereby cause the serrations 27 to be pressed into the surface of the core.

The upper ends of the casing 24 and the sleeve 25 are closed by end walls 30 and 31, respectively, and on the end wall 31 is an arm 32 that extends through an aperture 33 in the wall 30 and is pivotally connected at its upper end to a link 34 by a draw pin 35. The link 34 has an aperture 36 to accommodate a cable whereby the core remover may be raised and lowered.

The arm 32 and the link 34 carry sheaves 37 and 38, respectively. Sheaves 39 are also arranged on the opposite sides of the aperture 33 on the outer surface of the wall 30 at a lower elevation than the sheave 37 and in the same transverse plane as the sheaves 37 and 38. An endless cable or rope 40 is trained over the upper sides of the sheaves 37 and 38 and around the lower sides of the sheaves 39.

The arrangement of the cable and draw pin is such that when it is intended to lower the core lifter into the kerf the link 34 is connected to the arm 32 by the draw pin 35 and after the core lifter has been positioned correctly the draw pin 35 is removed. Lifting force may then be applied to the link 34 and the upward movement of the link will tighten the cable 40 and cause it to move the fingers 26 downwardly over the coniform surface 29 and into gripping engagement with the core.

The sleeve 25 is shown provided with bolts 41 that extend through the end wall 30 and have nuts 42 to seat against the end wall 30 for effecting relative longitudinal movement between the sleeve and the casing.

In accordance with the practice of the invention, the casing 24 is provided, on its lower end, with a plurality of legs 43 to seat upon the bottom of the kerf 22. On the end surface 44 of the casing between the legs 43 are apertures 45 that extend longitudinally of the casing to receive the ends 46 of a holder 47 which may consist of a resilient member, as for example round wire, of which the portion 48 lying exteriorly of the casing 24 is bowed.

The bowed portion 48 preferably lies rearwardly of the free ends of the legs 43 in order to avoid contact with the bottom of the kerf 22. Arranged on the inner side of the bowed portion 48 is a cartridge 49 of explosive material and said cartridge may, as shown, be lashed to the bowed portion by cords 50.

The cartridge 49 carries a detonator 51, and an ignition wire 52 is connected to the detonator

and extends upwardly through the core lifter. Preferably, the ignition wire is shielded by a conduit 53 arranged within the casing 24 to which it may be secured in any suitable manner.

In practice, an explosive cartridge 49 is secured to the holder 47 and the core removing device is then lowered into the kerf until the legs 43 seat upon the bottom thereof. The explosive cartridge 49 is then set off to sever the lower end of the core from the mass. Thereafter the sleeve 25 may be actuated into gripping engagement with the core which may then be lifted to the surface.

In the arrangement illustrated, only one holder for explosive material is shown. It will, however, be readily apparent to those skilled in the art that, in the event that it be intended to remove a core of large diameter, additional holders may be attached to the casing 24 to subject different points of the base of the core to the shocks of explosion.

I claim:

1. A core removing device, comprising a core

lifter to encircle a core and having apertures in its lower end, projections extending from the lower end of the core lifter, a U-shaped holder having its extremities extending into the apertures, and a charge of explosive material on the holder between the projections.

2. A core removing device, comprising a core lifter to encircle a core, projections on the lower end of the core lifter, a holder between the projections, a charge of explosive material on the holder, an ignition wire for the explosive charge, and a tubular shield for the ignition wire attached to the core lifter.

3. The core removing device, comprising a core lifter to encircle a core and having apertures in its lower end, projections on the lower end of the core lifter, a U-shaped holder between the projections having its extremities extending into the apertures, a charge of explosive material on the holder, an ignition wire for the explosive material, and a tubular shield for the ignition wire attached to the core lifter.

RAYMOND FRUTCHEY.

CERTIFICATE OF CORRECTION.

Patent No. 2,253,851.

August 26, 1941.

RAYMOND FRUTCHEY.

It is hereby certified that error appears in the printed specification of the above numbered patent requiring correction as follows: Page 2, second column, line 6, claim 1, strike out the words "between the projections" and insert the same after "holder" in line 3, same claim; and that the said Letters Patent should be read with this correction therein that the same may conform to the record of the case in the Patent Office.

Signed and sealed this 7th day of October, A. D. 1941.

(Seal)

Henry Van Arsdale,
Acting Commissioner of Patents.
